UNITED STATES PATENT OFFICE.

DAVID CHALMERS CULBREATH, OF LOS ANGELES, CALIFORNIA, ASSIGNOR TO WALTER E. RANDALL AND CHARLES P. MCFARLAND, BOTH OF LOS ANGELES, CALIFORNIA.

COIN-CONTROLLED VENDING MACHINE.

Application filed November 20, 1926. Serial No. 149,626.

The general nature of my present invention being indicated by the above title, I may state, at the outset, that this invention, in preferred embodiments, is suitable for use 5 in the vending of several varieties of stick gum, or the like; and it is an object of this invention to provide a simple and rugged coin-controlled gum vending machine in which a plurality of stacks of sticks of gum, or the 10 like, are so supported relatively to a gum chute as to permit of lateral delivery of successive lowermost sticks of gum from said stacks inwardly toward said chute. In preferred embodiments of my invention, the 15 coin slots are provided near said respective stacks of gum sticks, and the manipulation of a horizontal shaft, subsequently to the introduction of a coin or coins into one or more of said slots, is effective to occasion the 20 delivery into said gum chute of a number of sticks of gum corresponding with the number of coins used, and assorted, in variety according to the slots in which coins were inserted.

It is an object of my invention to provide 25 a gum vending machine, of the general character referred to, in which the mentioned parts, and additional fixed and movable parts, may be supported mainly or entirely 30 from a front plate in which the mentioned coin slots are provided; and, in preferred embodiments of my invention, the mentioned shaft being provided with a so-called oscillator, fixed thereon, and with one or more rotors, separately movable thereon, a bearing 35 element for said shaft may be supported directly or indirectly from a fixed part such as said gum chute.

It is a further object of my invention to 40 provide means, including the mentioned oscillator and one or more rotors, whereby the insertion of a coin through the mentioned slot, and its downward delivery through a coin guide (preferably secured to an external 45 surface of the mentioned gum chute) is effective to assure the advance of such rotor, through a predetermined angle, upon the oscillation of the mentioned shaft; and, in preferred embodiments of my invention, the 50 mentioned advance of a rotor being effective to operate, by cam means, a so-called kick-out lever delivering a single stick of gum at each movement into the mentioned gum chute (or delivering a plurality of sticks of 55 gum thereto, in one operation, in case coins

are inserted through different slots) the mentioned oscillator may be provided with means assuring the ejection of a coin therefrom and/or with a full-stroke mechanism serving as a ratchet dog constantly pressed 60 toward a corresponding rotor.

It is a further object of my invention to provide, in conjunction with the described parts or independently thereof, means whereby, upon the delivery of a last stick of gum, 65 or the like, from the mentioned supporting means therefore, any subsequent oscillation of the mentioned shaft, or its equivalent, is effective to advance a coin-excluding finger, or the like, across a corresponding coin slot, 70 in such manner as to prevent the insertion of coins after the supply of said sticks becomes exhausted.

Further objects and advantageous structural features of my invention, including 75 novel details of construction which enables many of the mentioned parts to be formed from sheet-metal and to be supported from the front plate of a vending machine, and including an advantageous use of pins upon 80 the mentioned rotors, to occasion not only a reciprocation of the mentioned kick-out levers but to hold the same, between operations, in positions favorable to the reception of additional coins, and including also a 85 full-stroke mechanism and means for limiting the movement of the mentioned oscillator to a predetermined arc, and including also advantageous means for holding mentioned parts in or returning the same to intended normal position of rest, may be best appreciated from the following description 90 of an illustrated embodiment of my invention, taken in connection with the appended claims and the accompanying drawings, in 95 which

Fig. 1 may be referred to as a front-to-back and median vertical section, taken substantially as indicated by the line 1—1 of Fig. 2.

Fig. 2 is a vertical section, amounting to a 100 rear view with a back plate removed, this view, being taken substantially in the plane indicated by line 2—2 of Fig. 1.

Fig. 3 is a partial vertical section comparable with the lower portion of Fig. 2 but taken from an opposite direction,—substantially as indicated by the lines 3—3 of Fig. 1 and Fig. 4.

Fig. 4 is a vertical section, amounting to 110

an elevation with one side removed, taken substantially as indicated by the lines 4—4 of Figs. 2 and 3.

Fig. 5 is a view showing, in dis-assembled 5 relationship, and as viewed in perspective from the general direction of arrow 5 of Fig. 1, a central oscillator and a pair of rotors hereinafter referred to as provided upon a horizontal operating shaft,—said oscillator 10 and said rotors being respectively provided with cooperating coin-receiving notches and slots.

Fig. 6 is a detail view which may be regarded as taken substantially as indicated 15 by the line 6—6 of Fig. 4 but on an enlarged scale—this view being pertinent more particularly to a coin-excluding device herein-after described as automatically operative upon the exhaustion of a supply of gum 20 sticks, or the like.

Fig. 7 is a perspective view of a follower hereinafter described as employed in effecting the mentioned final exclusions of coins.

Fig. 8 is a detail view, taken substantially 25 in the direction of the arrow 8 of Fig. 5, but showing more particularly an intended relationship of parts at the time a coin is inserted, an optional means of securing the mentioned oscillator to its operating shaft, 30 and means whereby a bearing bracket serves incidentally to limit the extent of rotation of said oscillator.

Referring to the details of that specific 35 two-stack embodiment of my invention chosen for purpose of illustration, although coin-controlled vending machines embodying my invention may have almost any desired external configuration, I show inner stack supporting or guiding elements 11, 11' 40 and cooperating outer, parallel elements 12, 12' as comprising flanges, 13 by which they may be secured, as by welding, to a vertical front plate of a housing 14,—this plate being optionally integral with side plates 15, 45 15' and optionally integral also with a bottom member 16 and a top member 17,—the mentioned top and bottom members being shown as corrugated in such a manner as to adapt the same to a decorative treatment, 50 such, for example, as to cause the entire housing to resemble an article of commerce.

The lower ends of outer guide elements 12, 55 12' or additional elements which may be formed of a similar material and secured thereto, being disposed in a horizontal plane or planes (as shown at 18, 18', Figs. 2 and 3) by extending these supporting members downwardly and inwardly, I may provide convergent lateral walls 19, 19' of a 60 gum chute 20,—shown as including also a rear wall 21, disposed opposite a gum delivery opening 22 and above a horizontal plate 23, serving as a bottom member for said chute.

65 Gum sticks 24 being disposed upon the

supporting members 18 and 18', and between the vertical guides, 11, 12 (and 11' and 12') by providing at the lower ends of the inner vertical guide elements 11, and 70 11' suitable lateral openings 25, 25' (optionally provided with lips 26, 26', therebelow, in order inwardly to direct successive sticks of gum, enabling the same to fall without damage into the chute 20, or its equivalent) I may employ any suitable 75 means, preferably subject to coin-control, for rendering the oscillation of a horizontal operating shaft, such as that illustrated at 27, effective, when executed subsequently 80 to the insertion of a coin or coins in suitable slots, to cause a corresponding delivery of sticks of gum into said chute.

For example, the shaft 27, or its equivalent is provided, not only with an external handle 28 but also with an oscillator 29, 85 shown as secured thereto by a set screw 30 (see Figs. 5 and 8) and the oscillator 29 is, in turn, provided with a coin receiving notch or notches 31, 31', I may also dispose upon said shaft one or more rotors 32, 33, 90 respectively provided with a plurality of peripheral coin-receiving notches 34 (on rotor 32) and 35 (on rotor 33) and with corresponding numbers of cam members, such as pins 36, 37,—the pins 36 being 95 adapted, upon rotation of the rotor 32, to operate a kick-out lever 38, movable beneath a stack 39 held by the guiding and supporting elements 11, 12 and 18; and the pins 37 being adapted to co-act, in a similar 100 manner, with an additional kick-out lever 40, operative beneath a stack 41 of gum sticks, or the like, confined between and supported by the corresponding elements 11', 12', and 18'.

In order to provide for the support of all parts from front plate 14, the kick-out lever 38 is shown as pivoted at 42 upon bracket ears 43, secured to the inclined wall 19 of gum chute 20, and as provided not only with a gum-engaging upper portion 44 (which is adapted, upon inward movement, laterally to remove a single stick of gum, or the like) but also with a somewhat complicated cam foot 45, provided with a main cam face 46 and with a subsidiary cam face 47,—these cam faces being so disposed that, upon each advance of the rotor 32, through an arc of 90°, engagement of a pin 36 therewith is effective to occasion an inward movement of the gum-ejecting upper portion 44 of the lever 38. The shape of the cam face 46 is moreover, such that, at the completion of an advance movement of the rotor 32, or its equivalent, two of the pins 36 co-operate in holding the same in its new position,—this position being, as hereinafter described, favorable to the reception of an additional coin and to a repetition of the described movements.

The kick-out lever 40, being pivoted on an axis 42' extending through ears 43' analogous to the mentioned ears 43, and being provided not only with a stick-ejecting upper portion 44' but with a cam foot 45', the last mentioned lever may be operated (by the pins 37) in a manner essentially similar to that described in connection with the lever 38; and said levers may be respectively provided with suitable means, such as tension springs 48, 48', secured respectively thereto, and to the ears by which the pivots 42' and 42 are respectively supported.

In order that the advance of a rotor or rotors of the general character described, upon oscillation of the shaft 27 or its equivalent, shall be contingent upon the previous insertion of a suitable coin through a slot or slots, such as may be provided in the front plate 14, or its equivalent (as, at 49, 49', opposite the upper ends of coin guides 50, 50', shown as secured to the respective side plates 19, 19' of the gum chute 20) the lower portions 51, 51' of said guides may be respectively disposed directly opposite a slot 34 in the rotor 32 and opposite a slot 35 in rotor 33, the respective notches 31 and 31' being invariably returned to a position such that an inserted coin, held partially within a notch 34 or a notch 35, is effective temporarily to key the rotor 32 and/or the rotor 33 (accordingly as a coin may be inserted into the slot 49 or the slot 49') to the oscillator 29, or its equivalent.

The notches 31 and 31' in the oscillator 29 are so formed as to assure the outward removal of a coin from a slot 34 or slot 35 in a rotor, by engagement of cylindrical or other cam face (53 and 53'), assuming the rotors to be held stationary, in the indicated manner, during the return of the oscillator 29 to its normal position of rest, in readiness for the reception of an additional coin; and both the shaft 27 and the fixed end of the spring 52 may advantageously be supported by means such as an arm 55, shown as secured to the side plate 19' of the gum chute 20 and as comprising both bearing extensions 56, for said shaft, and a spring-carrying finger 57, whose lower end 58 may be laterally deflected, in a manner favorable to the retention of the spring 52 thereon.

In order positively to limit the rotative movement of the oscillator 29, or its equivalent, I show a notch 59, into which the bearing extension 56 extends, as limited by surfaces 60, 60', disposed at right angles to one another; but it will be obvious that an equivalent effect might be obtained by the use of any suitable stop means.

In order that, after a coin is inserted, the said coin shall not be permitted to drop into the bottom of the described housing, or into a receptacle optionally provided therein (not shown) except upon the completion of such a

manipulation of the handle 28 as assures the delivery of a stick of gum, I may employ, in connection with a described rotor or rotors, any suitable full stroke mechanism. For example, I may provide such a mechanism in the form of ratchet dogs such as are shown at 61 and at 62, these dogs being shown as provided with coin engaging teeth 63, upon the lower surfaces thereof,—said surfaces having an arcuate configuration substantially concentric with the shaft 27 and being respectively provided with tension springs 64 and 65, tending to hold the same in coin-engaging position.

If formed of sheet metal the levers 44, 44' may be reinforced by means such as fins 66, 66'; and, in order to assure descent of the stacks 39 and 41 of gum, and also to prevent insertion of coins subsequent to the exhaustion of said stacks, the kick-out levers 44 and 44' being shown as respectively provided with slot closing fingers 67, 67', I may dispose upon the receptive uppermost sticks of gum constituting stacks 39 and 41 followers 68, of the general character best shown in Fig. 7. As best indicated in Fig. 6, a notch 69 in each of said followers may be so disposed that, when a follower descends to and rests upon a supporting surface 18 or 18', although the corresponding kick-out lever (44 or 44') is prevented from moving completely inward, it may be inwardly advanced sufficiently to throw its slot-closing finger (67 or 67') across the corresponding coin slot,—thereby preventing subsequent insertion of a coin.

It will be seen that each manipulation of the handle 28, or its equivalent, after the insertion of a coin and coins, must be effective under the described conditions, to deliver one or more sticks of gum into the chute 20 or its equivalent; and, in view of the shape of the coin guides 50, 50', including the downward extensions 51' thereof; and it is an important merit of the described organization that, if several pennies are inserted in either or both of the mentioned slots, the delivered sticks will be assorted consistently with the apportioning of said pennies between the mentioned slots even though manipulation of the handle 28 be subsequent to the insertion of several coins; and, so long as there remain pennies in both of the mentioned coin guides, each actuating movement of the handle 28 is effective to cause simultaneous delivery of a plurality of sticks of gum, or the like.

The general mode of operation of my coin-controlled vending machine having been indicated so far, as the same is unique, in connection with the foregoing description and summary, I emphasize in conclusion, the fact that various features of my invention might be independently employed; and also the fact that numerous modifications thereof

might be devised, by those skilled in the art. I claim as my invention:

1. In a coin-controlled machine suitable for use in the vending of flat sticks of gum, or the like: a main housing which comprises a front plate provided with coin-receiving slots; coin guides extending downwardly therefrom; a chute secured between a pair of said coin guides; means for supporting a stack of sticks relatively to each of said coin slots; a shaft rotatively mounted relatively to said guides; and means whereby rotation of said shaft subsequently to the descent of an inserted coin through one of said guides is effective to deliver a stick from a corresponding stack to said chute.
2. An organization of the general character defined in claim 1 in which said stack-supporting means comprises pairs of vertical stack guides secured to said housing and confining said sticks in end-on arrangement.
3. An organization of the general character defined in claim 1 in which said stack supporting means comprises inner and outer stack guides spaced apart, lower ends of said inner guides being so formed as to permit either simultaneous or successive inward deliveries of sticks from said stacks into said chute.
4. An organization of the general character defined in claim 1 in which said stack-supporting means comprises inner and outer stack guides spaced apart, lower ends of said inner guides being so formed as to permit either simultaneous or successive inward deliveries of sticks from said stacks into said chute, and in which said delivery means is effective simultaneously to remove a stick from each stack in case a suitable coin has been inserted in each slot.
5. An organization of the general character defined in claim 1 in which said chute comprises convergent side walls to which coin-guides are secured.
6. An organization of the general character defined in claim 1 in which said chute comprises convergent side walls to which coin-guides are secured, said side walls being respectively continuations of elements of said stack supporting means.
7. Means for supporting a stack of sticks to be vended; a chute; an oscillator disposed on a shaft and provided with a coin-receiving notch; a rotor movable on said shaft and provided with coin-receiving slots adapted to receive and to hold a coin in a position which renders the same engageable by said notch; means for oscillating said shaft; and means rendering rotation of said rotor, subsequently to the positioning of a coin in one of said slots, effective to cause delivery of a stick into said chute,—said notches in said

oscillator being so shaped as to cam said coin therefrom during a restorative movement of said oscillator.

8. Means for supporting a stack of sticks to be vended; a chute; an oscillator disposed on a shaft and provided with a coin-receiving notch; a rotor movable on said shaft and provided with coin-receiving slots adapted to receive and to hold a coin in a position which renders the same engageable by said notch; means for oscillating said shaft; and means rendering rotation of said rotor, subsequently to the insertion of a coin in one of said slots, effective to cause delivery of a stick into said chute,—said last-mentioned means comprising cam members, on said rotor, and a lever which is movable by said cam members and is provided with means for engaging a lower-most stick to remove the same laterally from said stack into said chute.

9. An organization of the general character defined in claim 8, in which said lever is provided with means normally holding said rotor in a coin-receiving position.

10. An organization of the general character defined in claim 8 in which said lever is provided with means whereby, upon the removal of the last stick from said stack, further insertion of a coin is prevented.

11. A coin-controlled vending machine comprising: a rotor; a lever movable by said rotor to deliver a vended article; an oscillator, adjacent said rotor and secured on a shaft carrying said rotor; means rendering a limited rotation of said oscillator, subsequently to the insertion of a coin, effective to advance said rotor; and means rendering a restorative movement of said oscillator effective to eject said coin therefrom.

12. Means within a housing for supporting a plurality of stacks of sticks to be vended; a single chute disposed between said supporting means; coin guides respectively provided with coin-receiving slots disposed below said supporting means; an oscillator disposed on a shaft toward which said coin guides converge and provided with coin-receiving notches therebelow; separate rotors disposed, on said shaft, below said coin guides and respectively provided with coin-receiving slots adapted to hold coins in positions rendering the same engageable by said notches; means for oscillating said shaft subsequently to the insertion of said coins; and means rendering consequent rotations of said rotors effective to deliver sticks from said stacks into said chute.

In testimony whereof, I have hereunto set my hand at Los Angeles, California, this 15th day of October, 1926.

DAVID CHALMERS CULBREATH.
